(57) **CLAIM**

We claim the ornamental design for a container tether, as shown and described in FIGS. 1 and 2.

DESCRIPTION

FIG. 1 is a perspective view of another container tether embodying the present invention;

FIG. 2 is a top view of the container tether of FIG. 1;

FIG. 3 is a bottom view of the container tether of FIG. 1;

FIG. 4 is a front view of the container tether of FIG. 1;

FIG. 5 is a rear view of the container tether of FIG. 1;

FIG. 6 is a left side view of the container tether of FIG. 1; and,

FIG. 7 is a right side view of the container tether of FIG. 1.

1 Claim, 3 Drawing Sheets
